UNITED STATES PATENT OFFICE.

JOHN R. STREID, OF KENMORE, OHIO, ASSIGNOR OF ONE-HALF TO ROY B. MEADE, OF AKRON, OHIO.

TOY GUN.

Application filed February 28, 1928. Serial No. 257,684.

The present invention relates to toy guns and has reference more particularly to a toy having its propelling power and its projectile in one element and constituted by a 5 rubber band.

The object of this toy is to provide a means of harmless pleasure with instructive effort.

Another very important object of the invention resides in the provision of a toy gun 10 of this nature which is exceedingly simple in its construction, strong and durable, exceptionally inexpensive to manufacture, convenient, compact, thoroughly efficient and reliable in use and operation, not likely to 15 easily become out of order and otherwise well adapted to the purpose for which it is designed so as to afford the maximum pleasure at a minimum cost for ammunition.

With these and other objects in view reference is now had to the accompanying drawings in which:

Figure 1 is a side elevation of the gun showing portions in section, and

Figure 2 is a top plan view thereof.

Referring to the drawing it will be seen that the numeral 1 denotes a handle or gun stock. The extension 2 simulates a gun barrel which is provided with a cavity 3 extending therethrough from top to bottom. A 20 somewhat triangular shaped hammer 4 is pivoted as at 5 in the cavity 3 and on one side is formed with a notch 6 and on another side with a shoulder 7. The numeral 8 denotes a trigger pivoted in the cavity as at 9. This 25 trigger is somewhat triangular in shape having one corner engageable with the shoulder 7 and the other corner engageable with the hammer for pushing the notch portion thereof forwardly when the trigger is swung in 30 the direction of the arrow in Figure 1 and by pressing the handle or finger 10 which extends from the trigger down outwardly of the cavity 3 so as to be conveniently engaged with the index finger or any other finger when the 35 hand grasps the stock or handle 1. The end of the barrel like extension 2 is formed with a notch 11. A rubber band is engaged by the numeral 12 and is shown in the notch 11 and in the notch 6 at which time it is under 40 tension and the shoulder 7 is engaged by one corner of the trigger 8. Obviously by swinging the finger piece 10 of the trigger toward the handle 1 the corner of the trigger is 45

released from the shoulder 7 and the upper portion of the trigger tends to swing the hammer 4 and release the rubber band thus doing away with the necessity of any springs or the like. 55

From the above detailed description it will be seen that I have devised a very simple toy gun which may be made of three pieces of wood and a couple of screws. The gun will be sufficiently strong to withstand use to which it would customarily be subjected by the child and will afford wholesome and 60 harmless yet highly entertaining amusement.

It is thought that the construction, utility, and advantages of the invention will now be quite apparent to those skilled in this art without a more detail description thereof. It 65 is apparent that changes in the details of construction may be restorted to without departing from the spirit or scope of the invention as hereinafter claimed or sacrificing any of its advantages. 70

Having thus described my invention, what I claim as new is:

1. A gun of the class described comprising a body having a cavity therein, a hammer pivotally mounted in the body and formed on 80 one edge with a shoulder and on another edge with a notch, the notch at one end of the body, a trigger pivotally mounted in the cavity adjacent the hammer and having a corner engageable with the shoulder and its opposite 85 corner engageable with the hammer to assist in rocking the hammer when the finger is actuated.

2. A toy gun of the class described comprising a body having a cavity therein, a triangular shaped hammer pivotally mounted in the cavity having its upper edge provided with a notch and its rear side edge provided with a shoulder, a triangular trigger pivoted in the cavity having one corner engageable 90 with the shoulder to hold the hammer cocked and its upper corner engageable with the hammer when the trigger is rocked to assist in rocking the hammer forwardly for releasing a rubber band engaged in the notch 95 thereof and a notch provided on the body. 100

3. A toy gun of the class described comprising a body having a cavity therein, a triangular shaped hammer pivotally mounted in the cavity having its upper edge provided with a notch and its rear side edge provided 105

with a shoulder, a triangular trigger pivoted in the cavity having one corner engageable with the shoulder to hold the hammer cocked and its upper corner engageable with the hammer when the trigger is rocked to assist in rocking the hammer forwardly for releasing a rubber band engaged in the notch thereof and a notch provided on the body,

said body having a handle extending downwardly therefrom at the end remote from that provided with the notch, and said trigger having a finger piece extending downwardly therefrom accessible by a finger of a hand grasping the handle.

In testimony whereof I affix my signature.
JOHN F. STREID.
